UNITED STATES PATENT OFFICE.

EMRY A. GOTTKO, OF BAYONNE, NEW JERSEY.

SOOT-DISTRIBUTER.

1,252,686.

Specification of Letters Patent. Patented Jan. 8, 1918.

Application filed February 5, 1917. Serial No. 146,751.

To all whom it may concern:

Be it known that I, EMRY A. GOTTKO, residing at Bayonne, in the county of Hudson and State of New Jersey, have invented a new and Improved Soot-Distributer, of which the following is a specification.

My invention has reference to attachments for gas fixtures and is more particularly designed for providing a simple, inexpensive and easily applied device adapted for being supported over the gas flame for distributing soot and other products of combustion and thereby prevent discoloration of the ceiling above the gas fixture.

My invention also has for its object to provide, in a device of the character stated, a rotatable sheet metal disk having radial vanes or blades and means connecting the outer ends of the said vanes for sustaining them in rigid relation and for preventing the disk blades from readily bending out of shape in handling the said disk.

With other objects in view that will hereinafter appear, my invention is an improved device of the character stated that embodies the peculiar construction and the novel arrangement of the parts hereinafter explained, specifically pointed out in the appended claim and illustrated in the accompanying drawing, in which:

Figure 1 is a perspective view that illustrates my invention as applied for use.

Fig. 2 is a plan view of the disk.

Fig. 3 is a cross section on the lines 3—3 on Fig. 2.

Fig. 4 is a plan view of the blank from which the disk is formed.

Fig. 5 is a detail view of the bracket member.

In carrying out my invention, I form a disk with a series of uniformly shaped and arranged vanes or wings 1 that radiate from a solid central portion 2, which at its center is provided with a tapered recess 20 on the underside, the purpose of which will presently appear.

3 designates a bracket, preferably a wire rod, the inner end of which removably engages a sheet metal band bracket 4 that clamps upon the fixture 5 in any approved manner, for example by a set screw 6 as shown in Fig. 1.

The outer end of the bracket terminates in a vertical bearing 30, the upper end of which is coiled into a horizontal loop 31 that terminates in a short beveled vertically projected

end bearing 32 for engaging the radial disk or wheel 1 in the manner clearly shown in Fig. 3, by reference to which it will be seen, that while the disk 1 is shown suspended on the bearing 32 only, which is the normal condition when the gas jet is on, the coil portion or loop 31 is so located, relatively to the flat central portion 2 of the disk, that at the slightest tendency of the disk to tip or wobble laterally, the said disk contacts with the loop 31 and is thereby held from being accidentally jarred off its bearing 32 under ordinary conditions, it being understood that the said loop 31 also serves as a support for sustaining the disk flatwise in place when the gas jet is turned off.

The disk or wheel 1 is formed from a blank sheet that is stamped to the shape shown in Fig. 4, from which it will be seen that a series of radial slits 21—21 are formed in the plate that extends from the central solid portion 2 thereof to a point near the peripheral edge and, at the said peripheral edge, each radial slit merges with a short circumferential slit 22, the said slits 22 being in annular relation and providing, as it were, an annular solid ringlike portion that forms a reinforcement for the outer edge of the disk.

By providing radial slits that merge with circumferential slits as shown, there are formed vanes or blades bent downwardly in a diagonal plane from the upper face of the disk, the said vanes being relatively so inclined with respect to each other to cause the wheel or disk to freely rotate when the hot products of combustion contact therewith when rising from the gas flame.

By providing the center of the wheel with a central bearing recess for receiving the tapered bearing 32 of the holding bracket and providing the said bearing end with a substantially horizontal loop, the wheel or disk is accurately centered and at the same time it is prevented from tilting over or off its bearing as it rotates thereon.

By forming the outer or peripheral edge of the disk or wheel with an annular solid ringlike portion, a rigidity is given to the disk and the vanes are held from being readily closed together should the disk, in falling, contact with the floor or from closing up under ordinary handling thereof.

While I have shown the clamp device as holding but one single bracket 3 to the fixture, it is obvious that the said device may

- be readily modified for holding a number of the said brackets, depending upon the burner brackets that may form a part of the gas fixture.
- 5 From the foregoing taken in connection with the drawing, the complete construction, the manner of its application and the advantages of my invention will be readily apparent.
- 10 The device is exceedingly simple in construction, can be easily applied to the gas fixture and when the disk is set in action by the hot products from the burners, the said products are readily distributed and are 15 prevented from rising and contacting with the ceiling.

Copies of this patent may be obtained for five cents each, by addressing the "Commissioner of Patents, Washington, D. C."

What I claim is:

An attachment for gas fixtures comprising a support adapted to be removably connected with a fixture, the said support consisting of a wire whose outer portion terminates in a vertically bent member, the upper part of which includes a flat coil, the free end of which terminates in a vertically extended tapered bearing, and a disk wheel 20 that includes a central flat portion having a central tapered seat for engaging with the tapered bearing of the support, the said disk including vanes that extend radially from the said flat portion of the disk.

EMRY A. GOTTKO.
